MARINE HATCH

Christopher C. Carlson, 2413 Via Pinale,
Palos Verdes Estates, Calif. 90274

Filed Oct. 16, 1967, Ser. No. 9,018

Term of patent 14 years

Int. Cl. D12—14

U.S. Cl. D71—1

FIG. 1 is a front elevational view of a marine hatch showing the new design;

FIG. 2 is a side elevational view;

FIG. 3 is a back elevational view; and

FIG. 4 is a sectional view taken on line 4—4 of FIG. 1.

I claim:

The ornamental design for a marine hatch, substantially as shown.
